UNITED STATES PATENT OFFICE.

ARTHUR EDWARD PRENTIS, OF KENT, ENGLAND.

MOP.

1,381,739.

Specification of Letters Patent. Patented June 14, 1921.

Application filed November 13, 1919. Serial No. 337,668.

To all whom it may concern:

Be it known that I, ARTHUR EDWARD PRENTIS, a subject of the King of England, residing in Bexley Heath, Kent, England, 5 have invented certain new and useful Improvements in Mops, of which the following is a specification.

This invention is for improvements in or relating to mops of the type in which 10 the fabric of the mop is dressed with fluid dressing. The latter may, for example, be either a polishing, cleansing or a disinfecting dressing, and such mops are particularly suitable for use on floors, such as those 15 covered with floor-cloth or made of parquet or other boards, and other surfaces.

A mop according to the present invention is characterized by a container for the dressing-fluid supported on a part of the mop 20 (for example a mop-head plate) when the mop is in use, combined with means to convey the fluid from the container to the mop-fabric.

In one embodiment of the invention, the 25 fluid is distributed in the mop-fabric through a perforated tube enveloped by the fabric.

In another embodiment of the invention, fingers are provided at or near the margin 30 of the mop-head plate (for example by slotting the marginal portions of the plate inward from its edge and bending some of the interslot portions up and some down), and a buffer-member, such as a length 35 of cord, is held in the guides to prevent scratching of walls or furniture in the vicinity of the surface to which the mop is being applied.

Preferably some of the guides serve only to position the buffer-member and some 40 serve as clips to hold it in place, and in one specific form of the invention a clip is constituted by a tongue formed integral with the plate and turned over to form a tubular spring grip for the buffer-member.

45 The invention also includes details of construction, for example the manner in which the fabric may be secured to the mop-head so as to be readily and quickly removed for cleaning, and the particular manner in which 50 the clips for the buffer-member are provided.

One preferred form of the invention will now be described in detail in connection with the accompanying drawings, although it is 55 to be understood that the invention is not limited by the constructional details so de-

scribed. Moreover, although a triangular mop-head is illustrated in the drawings, it will be understood that the invention can be equally well embodied in a mop of any other desired shape.

In the drawings—

Figure 1 is a plan view of the mop with all its parts assembled;

Fig. 2, on an enlarged scale, is a part section on the line 2—2 of Fig. 1 with the mop-fabric, handle-socket and buffer-member removed;

Fig. 3 is a plan of the mop head-plate of Fig. 1 looking from above, with the detachable parts removed;

Fig. 4 is a perspective view of a portion only of the mop-fabric, a clip for the fabric, and a fluid-distributing tube in their assembled relationship;

Fig. 5 shows in section a portion of a modified form of head-plate,

Fig. 6 is a perspective view of a portion of the head-plate showing a still further modification,

Fig. 7 is a sectional view of the parts shown in Fig. 4, and

Fig. 8 is a similar view of a slightly modified form of mop.

Like reference letters indicate like parts in the drawings.

As shown particularly in Figs. 1 and 3, a substantially triangular metal mop-head plate 1 has secured to one face of it, and disposed centrally near one side of it, a tubular socket 10 for a mop-handle. This socket is pivotally mounted, by lugs 11 and a pivot-pin 12, in upstanding arms 13 of a U-shaped strip of metal secured, by means of a rivet 14 to the underside of the plate 1 with its arms 13 projecting through slots in the plate. In the angle opposite the socket 10 strips of metal 2 are punched up to form clips to hold a triangular fluid-container 20 having an outlet nozzle 21. When the container 20 is held within the clips 2, the nozzle extends through a slot 3 to the underside of the head-plate.

On the underside of the latter, and around and near the edge thereof, is secured, in any convenient manner, a metal tube 30 bent or otherwise constructed to conform to the shape and size of the plate 1, as shown clearly in Fig. 3. The tube may be in the form of a continuous tube or, as shown in the drawings, in the form of a straight tube bent into the required shape and having its

two ends closed as at 31. The tube is perforated on its underside at 32 at intervals along its length and is also provided with an orifice 33 for the reception of the nozzle 21. The margin of the plate 1 is slotted at intervals in a direction normal to the edge, and the interslot portions are bent alternately up and down, as shown at 40, so as to afford fingers for holding or positioning 10 a cord or other buffer 50 which latter will extend beyond the fingers and will serve to prevent scratching, for example of furniture or of the walls in the vicinity of the floor or other surface upon which the mop is 15 being used. Preferably certain of the fingers, for example those designated by the reference character 41, are bent sufficiently far over or in such a manner as actually to grip the cord, the other fingers 40 merely 20 serving to position the cord around the edge.

As is customary in such mops, the fabric is preferably a strip of absorbent material 60, the edges of which are heavily fringed as at 61, and, as shown in Fig. 4, curved 25 spring clips 70 are preferably, although not necessarily, secured to the fabric. In the example shown, the fabric and the clips are secured by means of eyelets which may be augmented by sewing, but as such a method 30 of securing is well-known it has not been illustrated. The clips 70 are adapted to spring over and grip the tube 30 sufficiently securely, and in such a manner, that the fabric is held to the tube to envelop the 35 greater portion of its surface.

Alternatively the clips 70 may be separate from the fabric and the latter may be held between the clips and the tube 30, as shown more particularly in Fig. 8.

40 The fluid charged into the container 20 will flow therefrom through the outlet 21, which is conveniently controlled by an adjustable needle-valve 22, 23 to regulate the supply of fluid to the tube 30.

45 In operation, the mop-fabric will generally be first impregnated with the required fluid and similar fluid from the container 20 may, when necessary during the whole or any desired portion of the time 50 that the mop is in use, be allowed to flow through the nozzle 21 into the tube 30 by which it is distributed through the orifices 32 into the fabric. If the fabric is secured to the outside of the clips 70, as shown in 55 Fig. 4, the clips are perforated at 71 to permit the ready passage of the fluid to the fabric.

It will be seen, therefore, that the fabric is always maintained sufficiently impregnated with the required dressing which, but 60 for the adjustably controlled supply of fluid from the container 20, would otherwise gradually become used up by either use, evaporation, or both.

65 In Fig. 5 there is illustrated a section of

a small portion of a modified form of the mop. In the modified construction the mop-head plate 1 has its outer edge rolled over as at 300 to constitute a fluid delivery-tube 70 similar to the tube 30 in the previously-described construction. The tube 300 has outlet orifices 320 and will be in all respects similar to the tube 30. Fingers 400 for a buffer-member are in this case, however, not formed integral with the plate 1 but are 75 separate pieces secured to the plate by means of rivets such as 401.

Certain of the fingers 400 would be employed and so formed as to actually grip and hold the ends of the buffer-cord, as in 80 the case of the clips 41 of the previously-described construction.

Fig. 6 illustrates a still further form of the invention in which a modified form of clip for the ends of the buffer-cord is shown 85 to replace the clips 41 of Figs. 1 and 3. In this example the central portion of that edge of the plate 1 on which the clips 41 would normally occur, is extended in a tongue which is rolled over to form the tubular portion 410 which is sufficiently resilient to constitute a tubular spring grip 90 for the ends of the cord. The fingers 40 are provided as before and in fact may in all respects be similar to that described 95 in connection with Figs. 1-4.

Fig. 6 can also be taken to represent a similar construction when the tube 30 is constituted by a rolled-over edge, such as 100 300. In such a case the edge would be so cut and rolled over as to constitute a tube similar to the tube 30 and terminating, as at 31, and the portion of metal between these ends would be rolled over on the other side of the plate to constitute the grip 410. Obviously this portion, if insufficiently large, could be originally formed with the head-plate as a tongue extending from it.

One advantage of the present invention is 110 that it is not necessary to dip the mop-fabric from time to time into the dressing-fluid, nor to sprinkle it on or otherwise apply it to the mop-fabric, as the dressing-fluid may be supplied at all times as required from the container 20. Moreover, the fabric 115 and its springs are quickly and readily detached from engagement with the mop-head and may thus be used as a rubber or duster apart from the mop. Also the fabric and its spring clips may be quickly removed for 120 washing or otherwise cleansing.

It is obvious that modifications may be made in construction of the parts described. For example the tube 30 may be perforated with slits instead of round holes for the 125 escape of the fluid, the size and distance apart of such holes or slits varying according to the viscosity of the fluid used. Also the holes or slits can be formed either in the sides or in the bottom of the tube, or in 130

both the sides and bottom. Moreover, it is not essential to provide a buffer-member such as 50 and if this is omitted clips such as 40, 41 or 410 will not be necessary.

5 What I claim as my invention and desire to secure by Letters Patent is:—

1. A mop of the type described, comprising in combination a mop-headplate, a detachable closed fluid container separable 10 from and carried by the headplate, a perforated fluid-distributing conduit also carried by the headplate, means to convey fluid from the container to the conduit, and a mop-fabric engaging said conduit to receive 15 dressing fluid directly therefrom, the container being so disposed relatively to the conduit as to enable the fluid to flow to the latter by gravity when the mop is in use, substantially as described.

20 2. A mop of the type described, comprising in combination a mop-headplate, a mop-fabric, a container for dressing fluid supported on one face of said plate, a perforated conduit on the opposite face of said 25 plate, a quick release clip adapted to secure the mop-fabric to the perforated conduit, and means to convey fluid from the fluid-container to the said conduit.

3. A mop of the type described, comprising 30 a head plate, a mop fabric, a container for dressing fluid and a perforated conduit both supported by said head plate, a quick release clip in the form of a curved spring, said clip being adapted to secure the mop 35 fabric to the perforated conduit and of such dimensions as to spring over the perforated conduit and be retained thereon, and means to convey fluid from the fluid container to said conduit, substantially as described.

40 4. A mop of the type described comprising in combination, a mop-fabric, a mop head-plate, a container for dressing fluid and a perforated conduit both supported on the head-plate, said conduit being shaped 45 to correspond with the shape of the mop head-plate, means to secure the mop-fabric over the perforated portion of the conduit, and means to convey fluid from the fluid-container to the said conduit.

50 5. A mop of the type described comprising in combination, a mop-fabric, a mop head-plate, a container for dressing fluid and a perforated conduit both supported on the head-plate, the said conduit being 55 shaped to correspond with the shape of the mop head-plate, a quick-release clip adapted to secure the mop-fabric to the perforated conduit, and means to convey fluid from the fluid-container to the said conduit.

60 6. A mop of the type described comprising in combination, a mop head-plate, a container for dressing fluid and a mop-fabric both supported on the head-plate, means to convey fluid from the fluid-container to the 65 mop-fabric, fingers constituted by separated

marginal projections around the edge of the head-plate, some of the projections bent up and some down, and a buffer-member held in the fingers.

7. A mop of the type described comprising 70 in combination, a mop head-plate, a container for dressing fluid and a mop-fabric both supported on the head-plate, means to convey fluid from the container to the said fabric, fingers constituted by separated marginal projections around the edge of the head-plate, some of the projections bent up and some down, a buffer-member held in the fingers, and clips constituted by some of the marginal projections to retain the buffer- 80 member in place.

8. A mop of the type described comprising 85 in combination, a mop head-plate, a container for dressing fluid supported on the head-plate, a perforated conduit formed by rolling over the marginal portion of the head-plate, a mop-fabric secured to the perforated conduit, and means to convey fluid from the fluid-container to the said conduit.

9. A mop of the type described comprising 90 in combination, a mop head-plate, a container for dressing fluid supported on the head-plate, a perforated conduit formed by rolling over the marginal portion of the head-plate, a mop-fabric secured to the conduit, means to convey fluid from the fluid-container to the said conduit, marginal guides around the edge of the head-plate, and a buffer-member held in the guides. 95

10. A mop of the type described comprising 100 in combination, a mop head-plate, a container for dressing fluid and a mop-fabric both supported on the head-plate, means to convey fluid from the fluid-container to the mop-fabric, marginal fingers around the edge of the head-plate, a buffer-member to be held in the fingers, and a tubular spring clip to secure the buffer-member and to hold it in position in the fingers. 105

11. A mop of the type described comprising 110 in combination, a mop head-plate, a container for dressing fluid and a perforated conduit both supported on the head-plate, a mop-fabric, means to secure the fabric to the perforated conduit, means to convey fluid from the container to the perforated conduit, marginal fingers around the edge of the head-plate, and a buffer-member held in the fingers. 115

12. A mop of the type described comprising 120 in combination, a mop head-plate, a container for dressing fluid supported on the head-plate, a perforated conduit formed by rolling over the marginal portion of the head-plate, a mop-fabric, a tubular spring 125 clip of such dimensions as to spring over the perforated conduit and to grip the fabric between it and the said conduit, means to convey fluid from the container to the said conduit, marginal fingers around the edge 130

of the head-plate, a buffer held in the fingers, and means to hold the buffer in position in the fingers.

13. A mop of the type described, comprising in combination a headplate, a mop-fabric supported on said plate, marginal fingers around the edge of said plate, and a buffer member detachably held in said fingers, substantially as described.

10 14. A mop of the type described, comprising in combination a headplate, a container for dressing fluid and a perforated conduit both carried by said headplate, a mop-

fabric enveloping and detachably secured to said conduit, and means to convey fluid 15 from the fluid container to said conduit, substantially as described.

15. A mop of the type described, comprising in combination a headplate, a perforated conduit supported thereby, a mop-fabric, 20 spring devices for detachably securing said fabric to said conduit, and means for supplying fluid to said conduit, substantially as described.

In testimony whereof I affix my signature. 25
ARTHUR EDWARD PRENTIS.
